ATTORNEY

UNITED STATES PATENT OFFICE.

RAFAEL D. DE VILLEGRAS, OF ALLSTON, MASSACHUSETTS.

SHAVING BRUSH.

Application filed April 15, 1927. Serial No. 184,019.

My invention relates to shaving brushes.

The object of my invention is the production of a shaving brush having a detachable bunch of bristles, that is, a shaving brush, the handle of which is detachable from the bristles.

Another object of my invention is the production of a shaving brush, whose bristles are supplied with soap, so that the shaving 10 cups are thereby eliminated.

Another object of my invention is to produce an individual shaving brush, that is, a brush that is ready to be used just by moistening it with water, and may be detached from 15 the handle after use.

The invention will be hereinafter considered in detail and specifically claimed. Reference will now be had to the drawing forming a part of this application, wherein there 20 is illustrated a preferred embodiment of my invention, but it is understood that the elements thereof can be varied or changed as for shape, size, or form without departing from the spirit of the invention.

25 In the drawing I show a vertical sectional view of the brush showing the detachable handle and means to hold the bristles in the handle.

10 represents a handle preferably made of 30 soft rubber, with a broad flat bottom 11 and opening or neck 12' to receive the bristles.

The neck 12' of the brush is somewhat con-

stricted, for the purpose which will presently be explained.

The bristles are folded over on themselves 35 and are tied together by means of string or wire 13. The ends of the bristles are then dipped in a soap solution and are allowed to dry. The end 14 of the bristles is then inserted into the rubber head 10, which grips 40 the end and holds it tightly in place. The constricted neck 12' grips the bristles firmly and holds them in place.

From the above description it will be seen that a sanitary shaving brush is thereby produced, by means of which no other vessels are needed to produce a lather for a shave, and the cost to produce the bristles is so small 45 that the bristles may be removed and another set of bristles substituted after every shaving. 50

Having described my invention, what I claim is:—

In a shaving brush, the combination of a tuft of bristles comprising bristles folded over and tied together at the folded portion, 55 and a handle consisting of a single hollow member of yielding rubber having a neck portion provided with a restricted opening to receive said tuft of bristles, said neck being of such a diameter as to grip the tuft and hold 60 it in place and being deformable to permit the removal of the tuft and replacement of a similar tuft.

RAFAEL D. DE VILLEGRAS.
